PAPER FEED FOR ACCOUNTING MACHINES

Joseph M. McDonnell, Rochester, N. Y., assignor
to Remington Rand Inc., Buffalo, N. Y., a cor-
poration of Delaware

Application September 13, 1945, Serial No. 615,968

10 Claims. (Cl. 235—61.6)

1

The invention relates to the paper feed mechanism of accounting and like machines and more especially to the "long feed" mechanism for imparting occasional feeds to the paper of greater extents than the ordinary line spacing.

It is the principal object of the invention to improve apparatus of the indicated class in several respects which will be apparent from the following description and claims. The general organization of the mechanism has been improved, and provision is made for some operations not obtainable with prior devices of a similar type. Also some of the functions are accomplished by improved means, and provision is made for more flexibility in adapting or setting the mechanism to meet the various requirements of different pieces of work.

To the above and other ends, the invention consists in certain features of construction and combinations and arrangements of parts, all of which will be fully described herein and particularly pointed out in the claims.

By way of illustration, the novel mechanism is shown applied to the machine known commercially as the Powers alphabetic and numeric tabulator.

In the drawings,

Fig. 1 is a general right hand side view of the tabulating machine and showing some of the mechanism of the invention, the machine itself being shown in vertical section and with many parts omitted;

Most of the other figures are left hand views.

Fig. 2 shows the principal unit of the long feed mechanism as seen from about the middle of the machine, with some parts omitted and others in section or broken away;

Fig. 3 is a section through said unit on the line 3—3 of Fig. 10;

Fig. 4 shows a detail;

Fig. 5 is a view of the principal unit in section on the line 5—5 of Fig. 10;

Fig. 6 is a rear elevation, on a smaller scale, of the upper part of the machine showing elements of the invention applied thereto, some parts being omitted and others in section or broken away;

Fig. 7 is an exploded isometric view of the drive mechanism of the long feed device;

Fig. 8 is a fragmentary isometric view of certain linkages;

Fig. 9 is a detail right hand view of a portion of the line space control mechanism of the tabulating machine;

Fig. 10 is a developed longitudinal sectional

2

view of a portion of the drive mechanism, taken through the axes of three shafts;

Figs. 11 and 12 are views showing the clutch and the tripping devices isolated from other mechanism and in several positions;

Fig. 13 is a detail;

Fig. 14 is a schematic view of certain linkages;

Figs. 15—18 are similar small views of several linkages, each segregated from the others. Fig. 15 shows the so called "credit balance" linkage and the linkage for operating the line space device; Fig. 16 the "total linkage"; Fig. 17 the "slam bail" linkage; and Fig. 18 the "grand total" linkage;

15 Figs. 19—23 illustrate the successive positions of a certain "blank cycle link";

Fig. 24 is a plan view on a small scale, of the framework of the main unit of the long feed mechanism;

20 Fig. 25 is a segregated view of the line finding drive pawls and the means for restoring them after an operation of them;

Figs. 26 and 27 show samples of forms printed by the machine under control of the paper feed mechanism;

25 Fig. 28 is a partial rear elevation;

Fig. 29 is a time chart of the operation when, on listing items, the number of items exceeds the capacity of a form;

30 Fig. 30 is a time chart of the operation when the number of items just equals the capacity of a form and the total is printed on the overcapacity line of the same form. This chart is a continuation of a portion of Fig. 29 ending at line xx.

35 *The tabulating machine*

In the drawings, the invention is shown as applied to a Powers No. 3 alphabetic and numeric tabulating machine, of which Fig. 1 is a partial and more or less schematic illustration in section as viewed from the right. For brevity, this machine will be referred to herein as "the instant machine." It is described in the patent to Lasker & Mueller No. 2,323,816, and in the patent to John Mueller No. 2,381,361, August 7, 1945. It comprises a base section having side frames

50, on which rest the side frames 51 of the head section. A power driven worm shaft 52, indicated by a dot-dash line, drives the main base shaft 53 by a worm wheel 54. The shaft 52 also, through miter gears 55, upright shaft 56, miter gears 57 and worm shaft 58, drives the worm wheels 60 and 61, respectively, of a front head power shaft 62 and rear head power shaft 63.

An upward extension 64 of the shaft 56, also drives the paper feed mechanism of the present invention. This up and down shaft 56, 64 stands at an inclination toward the right hand side of the machine, as shown in Fig. 6 (toward the left in Fig. 6, which is a rear elevation). One rotation of the shafts 53, 62 and 63, is called a machine cycle. Degrees of a cycle are measured from the zero position shown in Fig. 1 at which the eccentric 65, which reciprocates the sensing pin box 84, is at its upper dead center.

Punched cards are fed by a picker 66 (Figs. 1 and 14) and feed rolls 67 from a hopper 68 into a sensing chamber 70, and thence by feed rolls 71 into a receptacle 72. The picker is reciprocated by a cam 73 on the base shaft 53, through a follower 74, arm 75, link 76, arm 77, spring 78, shaft 80, arm 81 and link 82. The cards are sensed by sensing pins 83 in a reciprocating pin box 84, and such of said pins as find holes, push upward set pins 85, whose motion is communicated by Bowden wires 86 in a "translator" 87, to code or "permutation" bars 88, which control a set of stops 90. In each denomination the stops 90 arrest a bracket 91 on a differential type bar 92, which slides on guide rods 93 and carries a set of numeric and alphabetic types 94. Said type bars are pushed up by springs and are restored by a restoring bar 95. Hammers 96 drive the types against the paper on the platen 97, mounted in the carriage 100. All of the mechanism above briefly mentioned is the same as is described in the Patent No. 2,323,816 and in the Mueller Patent No. 2,381,361.

The paper carriage 100 of the Powers machine, comprises a main bar 101 (Fig. 2), having secured thereto rails 102, grooved to slide on a fixed rail bar 103, which is mounted at its ends on a left hand frame bracket 104 (Fig. 6) of the usual kind, and a right hand frame bracket 105 (Fig. 3) here constituting a portion of the framing of the long feed mechanism.

Framing

Most of the driving mechanism of the long feed, is contained in a detachable unit, a plan view of whose frame is shown in Fig. 24 where it is viewed from the rear of the machine. See also Figs. 2 and 3. The casting 105 is the right hand frame-piece, and another casting 106 is the left hand frame-piece. The piece 105 has a front portion 1051 to which the carriage rail 103 is secured by a screw 1057, and from which the vertical web extends rightward at 1052 and thence rearward, to form the main portion of the frame piece. Said piece also has a projecting vertical wall 1053 (Fig. 6), which supports the worm shaft 64, as will presently appear. The member 106 has a vertical web with the usual bosses, and a forward projection 1061 (Fig. 2) secured to the rail 103 by a screw 1062. At their bottom portions, the castings 105, 106 have, respectively, horizontal walls 1054 and 1064 which overlap and are secured rigidly together by bolts 1065. This frame may be removed from the machine as a unit, by removing the screws 1058, 1057 and 1062.

The driving gear train

The driving gearing of the paper feed, comprises a worm 110 (Fig. 6) on an upper section of the shaft 64, which is journaled in blocks 111 bolted to the vertical wall portion 1053 of casting 105. Said worm drives a worm wheel 112 (Figs. 1, 7 and 10) which has a bearing on a stub shaft 113 secured by a nut to a bracket 114 (Fig.

24) fastened by screws to the blocks 111. The worm wheel 112 makes one turn per machine cycle, and it drives, directly or indirectly, three shafts, viz. the main paper feed shaft 115, the main cam shaft 116 and a counter-shaft 117 (Figs. 7 and 10). The counter-shaft 117 makes one rotation per machine cycle and the main shaft 115 in somewhat less than a machine cycle. These velocities may be obtained by any suitable gearing; but in the particular instance illustrated, they are produced by a rather roundabout arrangement, adopted here for certain technical reasons. The main shaft 115 is journaled in the frame-pieces 105 and 106 co-axially with the stub-shaft 113, whose end is adjacent to that of the main shaft. A sleeve 118 journaled on the two shafts, is rotatably coupled to the worm wheel 112 by a pin 120, and at its other end carries fast thereon a gear 121, meshing with a gear 122 fast on a sleeve 123 which is journaled in the frame piece 105 and in which the right hand end of the cam shaft 116 is journaled. The sleeve 123 is free on the shaft 116. Inside the frame 105, said sleeve carries a gear 124, meshing with a gear 125 fast on the main feed shaft 115. These two gears have, in the present instance, a ratio of six to five, so that the shaft 115 makes a rotation of 300° of machine cycle.

The cam shaft 116 is driven through the counter-shaft 117. The latter has bearings in the frame-pieces 105 and 106, and also in a block 126 fast on the frame bracket 114. It is driven by a pair of gears 127 and 128, fast, respectively, on the worm wheel 112 and the shaft 117. Said shaft has thereon a gear 130, meshing with a gear 131 which has riveted thereto another gear 132, the gears 131 and 132 being free on the shaft 115 and differing slightly in size. The gear 132 meshes with a gear 133, keyed on the cam shaft 116. The gear-pair 131, 132, stands between a collar 134 pinned to the shaft 115, and a collar 135 secured to said shaft by a set screw. The shafts 115 and 116 are timed shafts and it is important that they occupy, initially, fairly exact relative angular positions, and, as it is difficult to secure such exact positions by tightening a set screw, the form of gearing described, greatly facilitates the required initial adjustment. The gears 130 and 131 therefore have 36 teeth each, and the gears 132 and 133, 39 teeth each, of the same pitch. In assembling the mechanism, the shafts 115 and 116 are first adjusted exactly to their correct relative positions with the gear pair 131, 132 out of mesh. Said pair is then slid along the shaft 115 into mesh. The teeth will probably collide on the first trial, but by turning the pairs of gears slightly, an angular position will be found where they slide into mesh easily. They are then secured by tightening the set screw in the collar 135.

Keyed on the shaft 115 (Fig. 10) is the long hub 136 of a five-notched clutch disk 137; and journaled on the left end of said hub is a drive disk 140 which (Figs. 7, 11 and 12) carries the co-operating clutch pawl 141. This disk is normally at rest in an angular position determined by a detent consisting of an arm 142 (Fig. 2) carrying a roller 143, spring pressed into a notch in the disk; and whenever a long feed of the paper is required, the clutch pawl 141 is caused to engage the disk 137 and impart one rotation to the disk 140. The projecting left hand end of the shaft 115 carries a sleeve 144 (Fig. 10) held on by a nut 145, which sleeve is in effect a part of the shaft.

Loose on said shaft (or on said sleeve) is a unit herein called the drum, designated generally 146. It is built up of a hub or sleeve 147 having keyed thereon several notched disks 148, 150, 151 and 152, a gear wheel 153 and certain other devices to be mentioned hereinafter. By means to be described, a rotation of disk 140 imparts differential extents of rotation to this drum. The gear 153 meshes with a gear 154 (Fig. 7) on a horizontal shaft 155 which, by miter gears 156, inclined shaft 157, and miter gears 158, rotates the shaft 160 of the paper cylinder or platen 97. Vice versa, any rotation of the platen, as by hand or other means, is communicated to the drum 146. The miter gears 156 and 158 and the shaft 157 are covered respectively by housings 1561, 1581, and 1571 (Fig. 6). In the instant apparatus the cylinder 97 and its pressure rolls are the means that immediately propel the paper, though it is now more common, in these machines, to do that by more accurate sprocket-like devices, also geared to the drum 146, the cylinder 97 acting merely as a platen.

The drum 146 is removable and replaceable by merely sliding it off of or onto the shaft 115, it being retained in position by a latch 161 (Figs. 6 and 10) pivoted to the gear 153 and engaging in an annular groove 162 in the shaft. The gear 154 is not mounted directly on the shaft 155, but is mounted fast on a sleeve or hollow shaft 163 (Fig. 10) which has a bearing in the frame casting 106. The shaft 155 is polygonal in cross section and passes through a polygonal axial opening in the sleeve 163, whereby the sleeve is in effect splined on the shaft, so that the latter can be slid lengthwise through the sleeve. Said shaft at its right hand end is journaled in a bracket 164 (Fig. 6) which is secured to the main bar 101 of the carriage. The construction is such that the carriage may be slid lengthwise to different positions on its fixed rail 103, and the shaft will slide with it, moving through the sleeve 163 without affecting its geared connection with the drum gear 153.

The gear ratio between the gears 153 and 154 is usually made such that one complete rotation of the former feeds the paper the length of a form. In a common case, the gearing is adapted to forms of a length of eight and one half inches, or 51 single line spaces. One rotation of the platen of the Powers machine feeds the paper 30 spaces, and the gears 153 and 154 are accordingly made in the ratio of 51 to 30. If the gear 153 was made with 51 teeth and the gear 154 with 30 teeth, then each tooth of the gear 153 would correspond to a line on the paper.

In Fig. 10, three spur gears of different diameters are shown mounted on the sleeve or hollow shaft 163, of which the smallest is gear 154, which is of a diameter to feed the paper 51 single spaces to one revolution of the drum 146, the second gear, 1541, is of a diameter to mesh with a gear on the drum smaller than the gear 153, so as to afford a 1:1 ratio between the drum and the shaft 163. This would feed the paper 30 spaces per revolution of the drum. The third wheel 1542 would similarly afford a feed of 21 spaces per drum revolution, and, therefore, be suitable for forms of that length. The illustrated arrangement would be adapted for a customer who used forms of the three different lengths mentioned. The drum for the 30 line (five inch) forms would have its gear mounted on the drum in the plane of the gear 1541; and the

drum for the 21 line (three and one half inch) forms would have its gear in the plane of the gear 1542.

5 *The line finding drum and its drive pawls*

Each of the disks 148, 150, 151, and 152 has in it a notch, as 1521, (Fig. 2), and these notches are spaced angularly apart distances appropriate to the predetermined lines to which the paper is to be fed by the long feed mechanism. Thus if the first line of a heading is to be printed on line-space 6 on the paper, (Fig. 26) the first item on line 14, and the total at the bottom of the form on line 42, then one of the disks would have a notch to bring the paper to line 6, another disk would have its notch arranged behind the first an angular distance equal to eight fifty firsts of its circumference, to bring the paper to the first item line 14 and a third disk would have a notch spaced 36 tooth spaces behind the first, to bring the paper to the bottom line, line 42. This arrangement will be understood from the following description. In general, a drum is made up of the required number of line finding disks, which in the process of assembling, are turned to bring their notches into the relative angular positions required by the work in hand, and the whole is secured rigidly together by rivets 159 (Fig. 10) passing through the disks and through a flange on the sleeve 147.

The means whereby the disk 140, when rotated, drives the drum 146, including the gear 153, will now be described. Said disk has several posts or studs projecting from its face over the disks 148-152 of said drum. On the stud 165 there are pivoted four pairs of pawls, 166 and 167, one pair in the plane of each of said disks; each pawl being drawn toward its disk by a spring 168. In Fig. 2 the proximate pair are broken away to show the pair behind them. On a stud 170 there are pivoted spring pressed latches 171, one normally engaging each of the pawls 166 to hold the latter out of engagement with its disk. In each pair a stud 172 on pawl 166 holds the pawl 167 out of engagement until the former itself moves in. The pawl 166 has its tooth 173 abrupt on its advancing edge, to push the disk around, and the pawl 167 has its tooth 174 abrupt on its opposite edge to prevent overthrow of the disk when the pawls are arrested. In operation, a long feed is initiated by tripping one of the pawls 171 and closing the clutch. Usually, the notch is not in the stop position shown in Fig. 2, but may be anywhere in the circumference of the disk. The pawl teeth 173 and 174 will then ride idly on the surface of the disk until they reach and snap into the notch. They will then turn the drum the balance of a rotation, always arresting it in the position shown. When any notch is in that stop position, the paper is in the line space position for which that notch was set in making up the drum.

The pawls 171 are tripped by several tripping levers 175, one for each such pawl, said levers pivoted on a fixed stud 176, (Figs. 11 and 12) and rocked to normal position by springs 178. Each tripping lever has a stud 179 which, when the lever is fully operated, rocks the associated latch 171 to release the line pawl 166.

The tripping levers 175 may be operated selectively at times appropriate to the work in hand and by means depending on the machine to which the invention is applied. One may be operated 75 before the printing of a total in order to print

the total at the bottom of a form, or just after total printing in order to feed the paper to the next form, or after printing on the last line of the form, or, when desired, after the sensing of a control hole in a card; or at other times, as required. The mechanism is thus readily adaptable to a variety of situations and of uses.

The mechanism thus far described is, in principle, substantially the same as that described and claimed in the prior application for Letters Patent filed February 17, 1944, by John Mueller and Joseph M. McDonnell, Serial No. 522,720, which issued April 26, 1949 as Patent No. 2,468,341, though it differs somewhat in detail and design.

Means to operate the tripping levers and clutch

The means to control the tripping levers 175 and the clutch are of novel and improved construction. Said levers have three positions. They stand normally as shown in Fig. 2 and in full lines in Fig. 11. To initiate a long feed, the selected one of them is first "set" that is to say, it is rocked to the broken line position of Fig. 11, after which, at the proper time in the cycle, it is swung further to its effective tripping position shown in Fig. 12; and at the same time it trips the clutch to start the feeding operation. The clutch pawl 141 is normally held away from the disk 137 in the usual way by a lever or clutch dog 180 (Fig. 11) pivoted on a fixed stud 181 and having a spring 182. Said dog or pawl has a post 183 projecting across all of the tripping levers 175. Each of said levers has a curved arm 184 with an abrupt end edge 185. A universal operating bar 186 extends across the rear of the row of tripping levers, said bar being carried by an arm 187 fast on a rock shaft 188 journaled in the frame casting 106. Inside said casting, the rock shaft has an arm 190 carrying a follower roller 191 controlled (Fig. 3) by a cam 192 on the cam shaft 116, and by a spring 193. During the major part of a machine cycle, the bar 186 stands as shown in Fig. 2, but in the mid part of each cycle, it is oscillated clockwise and back moving over the tops of the arms 184 of the unset tripping levers. When, however, one of said levers has been set, the bar 186 will contact the edge 185 of that lever, and swing the lever to its effective position shown in Fig. 12, the stud 179 on the lever then tripping the associate latch 171 and freeing the associate drive pawl 166 for operation. When the tripping lever 175 moves to its dotted line position of Fig. 11, its curved arm 184 encounters or approaches the post 183 on the clutch dog 180; and when said lever receives its final movement from the bar 186, this arm 184 rocks the lever 180 to trip the clutch. It will be seen that the clutch is tripped by the tripping lever 175, and will not be operated unless one of said levers is set. Also, that any tripping lever may be set at any time while the bar 186 is at rest, and then, at the proper instant in the machine cycle, the line-finding pawl will be released and the clutch tripped by the action of the tripping bar 186. When the bar 186 swings forward, it moves over the arms 184 of un-set tripping levers and prevents them from being set at that time. A prolongation of the bar 186 normally lies just beneath an arm 194 of the clutch dog 180 (Figs. 2 and 11) and positively prevents the tripping of the clutch when said bar is in its normal position.

The mechanism above described for tripping the feed pawls and the clutch, is an improvement

over that described in the prior application Serial No. 522,720.

Restoring the drive pawls

- 5 In order to restore the drive pawls 166 and 167 after an operation thereof, a rock shaft 195 (Figs. 2 and 25) journaled in the frame casting 106, has, just outside said casting, an arm 196 from which a post 197 (Fig. 25) projects and stands in front of the upright arms of all of the pawls 166. At the proper time in the cycle, this arm and post are rocked clockwise by a cam 198 (Fig. 3) on the cam shaft 116, acting on a follower roller 200 on an arm 201 fast on the shaft 195 inside the casting 106.

Means to set the tripping levers

The tripping levers 175 may be set by a variety of means depending on the machine to which the mechanism is applied and on the particular job to be done. Several such means will be described herein. As shown in Figs. 2 and 6, four rock-shafts herein called "tripping shafts," 202, 203, 204, and 205, arranged in a vertical tier, have each an arm 206 to which is pivoted a push rod 207 whose upper end lies beneath an ear formed off from an arm of one of the tripping levers, so that a rocking of one of said shafts will set its associate tripping lever. The rods 207 are guided in a fixed bracket 208. A fixed post 209 beneath the shaft 205, acts as a stop for an arm of said shaft.

Means are provided whereby any of the three shafts 203, 204 and 205, may be rocked under the control of a hole in a record card. Each of said shafts has an arm 210 (Figs. 11, 13 and 28) connected by a link 211 (Figs. 1, 2 and 6) to an arm 212 on one of three transverse rock-shafts 213 pivoted in brackets 214 at the back of the tabulating machine. Each of said shafts has an arm 215 connected by a link 216 with a lever 217 pivoted on a post 218 in a guide bracket 220. The three levers 217 are of different lengths and each of them has an ear in position to be operated in a well known manner by one of the Bowden wires 86 in the translator 87. When a card having a control hole is sensed, the appropriate lever 217 is rocked, rocking the associate shaft 203, 204 or 205. In the Powers machine the Bowden wires and, therefore, the train of connections just described are set near the end of a cycle and are locked in set position until near the end of the next cycle, so that the tripping lever 175 will be retained in the position shown by broken lines in Fig. 11, until operated by the bar 186.

In order to make the mechanism flexible in its applications the arms 206 may preferably be operatively disconnectable from their shafts. The disabling devices used for this and similar purposes, as shown in the drawing, are of a familiar type. The hub of arm 206 is loose on its shaft, and lying beside said arm is another arm 221 whose hub is fast on the shaft. Said arm 221 (Figs. 13 and 28) carries a housing in which is a spring-pressed plunger 222, the stem of which has a finger button 223. When this plunger occupies its inner position, its inner end engages in a hole in the arm 206 and locks said arm 206 to the arm 221 and renders the former operable. To disable the arm 206, the plunger is retracted and turned so that a stud or tooth 224 thereon rests on top of the housing and prevents the plunger from entering the hole in the arm 206. A number of these disabling devices are used in the mechanism, and for brevity they will be called herein "dis-

abling buttons." In setting up the mechanism for a particular job, any one of the four tripping shafts may be rendered incapable of initiating a long feed of the paper by setting its plunger 222 in its withdrawn position.

Operation of the feed mechanism

It may be advisable at this point to describe in detail the mode of operation of the mechanism as thus far described. For example in the form shown in Fig. 26, two or more lines of heading are printed, beginning at line 6 of the 51-line form, each line, of course, being printed in one cycle. The card for printing the last heading line has a control hole in order to cause the paper to be fed from there to line 14. This card is sensed in the latter half of the cycle preceding the one in which the last heading line is printed, the control hole causing a Bowden wire 219 (Fig. 6) to thrust upward the plunger 229 located on the translator, rocking the frontmost one of the three levers 217, and the upper one of the rock shafts 213. The latter, through its link 211, rocks the tripping shaft 203, which, through its push-rod 207, sets the second one of the tripping levers 175 as shown in broken lines in Fig. 11 viz., the one associated with the disk 150 (Fig. 10). This occurs at about 330° of said preceding cycle. The Bowden wire 219 remains in its raised position until near the end of the last heading cycle. Printing occurs at about 165° of cycle. The universal tripper frame 186, 187, starts to advance at about 126° and reaches its fully operated position shown in Fig. 12 at about 176°. In that advance movement, the arm 175 trips the latch 171 and releases the second one of the four feed pawls 166, which falls onto the line-finding disk 150. This disk has its notch 1501 so disposed that when it is turned to the position of the notch 1521 in Fig. 2, line 14 of the form is at the printing line. The tripping lever 175, in advancing to its fully operated position also acts on the post 183 (Figs. 11 and 12) to trip the clutch dog 180, and close the clutch. A notch of the clutch disk 137 picks up the pawl 141 and starts the disk 140 into rotation at about 186° of cycle. A rotation of said disk occupies 300° of cycle, ending at about 126° of the following cycle. As the disk 140 rotates, the feed pawl 166 slides around the disk 150 until it drops into the notch 1501, whereupon it carries with it said disk and the gear 153, which, through the described train of gearing, feeds the paper to line 14. Meanwhile, at from about 196° to 226°, the universal tripping frame 186, 187 has returned to its normal position. When, near the end of the cycle, the Bowden wire 219 returns to normal, the train of linkage ending in the push rod 207 also returns, allowing the tripping lever 175 to return to normal. Also, the restoring bar 197 operates, reaching its forward peak position at about 176°. This was at near the time when the pawl 171 was tripped; but the restoring frame receded from its advanced position before the tripping frame 186, so that the pawl 166 was released. It will be noted that an operated pawl 166 is restored by the bar 197, not immediately after the completion of a revolution of the disk 140, but a few degrees of cycle later and just prior to the time when one of said pawls 166 would be released for a new operation.

It will be seen that a tripping lever 175 may be set to its broken line position of Fig. 11 at any time after the universal frame 186 has receded out of the way (say at 214° of cycle) and before said frame advances in the next cycle. When so

set, it will be fully operated by said frame, tripping its latch 171 and the clutch dog 180, at the proper time to start a feeding operation.

If, for some reason, the user of the apparatus may wish, on some run of the cards, to print the first item directly beneath the last address or heading line without any intervening long feed, notwithstanding the last address card is punched with the control hole, he may accomplish that by merely withdrawing the disabling button 223 on shaft 203. Moreover, he may have other sets of cards in no way related to those above referred to and with which he uses another translator.

The timings given in the description and in the timing diagram, are approximate only, and are only illustrative.

Capacity feed

On the form shown in Fig. 26, it is not desired to print any item below line 40; and in case there are further items to be printed, the paper is fed to line 14 of the next form, skipping the heading. In the illustrated mechanism, this is done by the line-finding disk 152, which is the one nearest the reader in Fig. 2 and most remote in Fig. 7 and which is rotated to the position shown in the former figure to feed the form to the first item line.

A rock shaft 225, herein called the capacity shaft (Figs. 2, 3 and 5) is journaled in the frame castings 105 and 106, and it has fast on its projecting left hand end a plate or arm 226 (Fig. 2). Inside the frame 106 said shaft has fixed thereon an arm 227, shown (mostly in broken lines) in Fig. 3, to which is anchored a spring 228 tending to rock the shaft clockwise. Farther within the frame 106 (Fig. 5) said shaft has fixed thereon an arm 230 with a follower roller 231 for cooperation with a cam 232 on the cam shaft 116, which cam, when it acts, rocks the shaft 225 counter-clockwise. Said shaft 225 and its arms normally stand in their counter-clockwise position where they are retained, against the tension of the spring 228, by a stepped latching member 233 (Fig. 2) engaging a corner of the arm 226.

When the latch 233 is swung downward about its pivot post 234, the spring 228 turns the shaft 225 a short distance clockwise until the corner of the plate-arm 226 is caught in a second notch 235 of the latch member and also swinging the follower roller 231 down onto its cam 232. When the shaft 225 rocks clock-wise a nose 236 mounted on the arm 226, acting on a post 237 projecting from the particular tripping lever 175 shown in Fig. 2, sets said tripping lever; that is to say, it swings said lever to the intermediate or set position hereinbefore described; thus preparing for a paper feeding operation by the line-finding disk 152.

The latch 233 is tripped by a cam or arm 240, consisting of a ring of sheet metal mounted in the drum 146 and in the position indicated in Fig. 10; and this ring has a projecting arm which revolves with the drum. It is indicated in dot and dash lines in Fig. 2 in the position it occupies when the paper is at the capacity line (line 40 in Fig. 16) of the form. When the paper is line spaced to the over-capacity line 42, the arm 240 trips the latch 233 by acting on a finger 241 on said latch. In order to permit reverse rotation of the drum 146, including the arm 240, said finger is pivoted to the latch and controlled by a spring 242 anchored to said finger and to the arm 226. Said spring presses an arm of the finger against 75 a limit stud 243 on the latch, and it also serves as

11

the spring to pull the latch member itself into engagement with the arm 226. The construction is such that, if the drum is turned backwards, the finger will yield to the arm 240, turning about its pivot to let the arm pass.

The capacity feed mechanism, as thus far described, would operate as follows: The line space device operates soon after printing, and, in case of over-capacity, trips the latch 233 at 214° of cycle. At this time, the universal tripping member 186 has already made its advance movement and is returning to normal position. The long feed will not begin, therefore, until the next advance of said member and actual rotation of the feeding disk will begin at 186° of the next cycle after that in which the item is printed on line 40. After the feed has been started, the shaft 225 is restored to its normal position by the cam 232, and retained there by the latch 233. The mode of operation just described is satisfactory in many instances. However, by other mechanism to be presently described, it is modified in certain respects so as to give better results in cases where total taking operations are involved.

The cam 232 (Fig. 5) has on it two restoring humps 2321 and 2322, the former restoring shaft 225 at around 286° of cycle and the latter at about 102°. Both of these humps act during the period between 214° of one cycle, when the latch 233 is tripped, and 126° of the next cycle, when the universal frame 186 begins its advance to initiate the feeding of the paper. Referring to Fig. 2, the arm 240, when it operates on the finger 241 of the latch 233, only moves one line space, which, however, may be a single, double, or triple line space distance. Said arm has a blunt end of such dimensions that that amount of rotation of the arm will depress the finger but will not move clear past and free of the finger. The arm therefore holds the latch depressed until the long feed begins, when it moves past said finger and allows the latter to return to engagement with the arm 226. The oscillations of this arm by the first passage of the humps 2321 and 2322, therefore do not prevent the feed from taking place. After the feed starts the hump 2321 will restore the parts at 286°.

On a long feed following a total, the paper is fed from some line of one form to a line of the next form, in the course of which the arm 240 would trip the latch 233 but would pass beyond it and immediately release it. The capacity shaft would thus be tripped, but would be effectually restored by the next hump on the cam 232, and no capacity feed would result.

In the specific form illustrated, the capacity feed disc 152 brings the paper to the first item line of a form, the same as does the disc 150 operated by the trip shaft 203 under card control. When such is the case the trip shaft 205 which also operates disc 152 can be utilized to feed the paper from the last heading line of a form to the first item line of the next form under card control, permitting the disc 150 to be used for some other purpose.

Total taking

Some of the long paper feeding operations are associated in one way and another with the taking of totals, and before describing those operations it is necessary to describe some of the mechanism of the Powers alpha and numeric (or No. 3) tabulator to which the long feed mechanism is shown applied in the instance illustrated in the drawings.

12

Each type bar 92 (Figs. 1 and 14) is controlled at times by a "slam bail pawl" 245 which is itself controlled by a control bar 246, mounted for a short sliding motion front and back of the machine. There is a row of these pawls and bars clear across the whole series of type bars. In Fig. 14, the bar 246 is held forward, and a spring 247 anchored thereto is pressing the pawl 245 into engagement with the rack teeth of the bar. In this position the pawl prevents rising of the bar but, if the bar were already in an upper position, the pawl would permit downward motion of it. The control bar is itself urged rearward by a spring 248, and if allowed to yield thereto, moves rearward until its rear end presses the pawl 245 out of engagement with the rack, (Fig. 1).

Beneath the tier of control bars 246 are four rock shafts, viz., a "grand total shaft" 250, a "total shaft" 251, a "slam bail shaft" 252 and a "designation shaft" 253. Each of these has fast thereon an upwardly projecting blade 254, extending beneath all of the bars 246 and each sweeping toward the front of the machine when the shaft is rocked clockwise in Fig. 14 (counter-clockwise in Fig. 1). Pivoted to each control bar are three connectors 255, 256 and 257, each settable into active and inactive positions. In the setting shown, the connectors 255, and 256 are inactive; but if connector 256, for example, was turned clockwise in Fig. 1, its heel would come into the path of movement of the blade 254 on the rock shaft 251. Said shaft is rocked counter-clockwise in Fig. 1 preparatory to and during every total-printing cycle, and its blade would move the bar 246 forward and lock that particular type bar against rising in total printing cycles. The connector 257 has a spring pressing a nose on its forward end into engagement with a differential detent 258 having three notches at different distances from its pivot. This detent and connector are shown set so that the latter has its rear end in position to be controlled by the slam bail shaft 252, which shaft is shown in its normal position in Fig. 1, with the pawl 245 out of engagement, and in rocked or "pulled" position in Fig. 14, where it has moved the pawl into engagement to prevent the type bar from rising. The connector 257 can also be set to an inactive middle position and to a third position where its hook-like front end is in position to be acted on by the blade 254 of the designation shaft 253.

A total taking control unit 260 (Fig. 15) mounted on top of the right hand base frame 50, has two cam shafts, viz., a total shaft 261 and a grand total shaft 262, each carrying certain cams which control functions of the machine in total taking operations. The total shaft 261 has a one-revolution clutch through which, when closed the shaft is geared to make one revolution in two cycles, viz., a blank cycle and a total cycle. The shaft 262 has a similar clutch and when the latter is closed said shaft is geared to make one revolution in three machine cycles, viz., a blank cycle, a total cycle and a grand total cycle. Figs. 14 and 17 show the slam bail cams 263 and 264 on the total and grand total shafts, respectively. These cams have follower rollers on follower levers 265 and 266 respectively, said levers being operatively connected at their inner ends so that a rocking of either of them will be communicated through the link 267, lever 268, link 270, bell crank 271 and link 272, to "pull" (rock clockwise) the slam bail shaft 252. This linkage is connected through a short link 273 with an arm

on shaft 253 to rock the latter shaft also. The link 273 is connected with said arm on the designation shaft 253 by pin and slot to allow of said shaft being independently pulled by other means.

In most ordinary set-ups of this machine, all type bars in adding columns have their control bars 246 put under control of the slam bail shaft 252 by setting the connector 251 as shown in Fig. 14 and all type bars used for printing alphabetic and other designatory matter are put under control of the designation shaft 253 by setting their associate connectors 251 each with its front hook-like end in the path of the blade 254 on said designation shaft.

The type bars begin to rise at 33° of cycle, are at their highest points at before 158°, and are fully restored by 283°. When, therefore, the linkage 267—273 is pulled early in a cycle, all of the type bars set up as just described, will be locked down by their slam bail pawls 245, and no printing from them will occur during that cycle. The cams 263 and 264 pull this mechanism early in the blank cycle of a total taking operation and hold it pulled until late in the cycle, and pull it again a little before the middle of the total cycle so as to engage the pawls 245 with the bars while the latter are in elevated positions, so as to prevent slamming of the adding type bars when the totalizers are withdrawn from the racks. In grand total operations, this mechanism is pulled nearly throughout the blank cycle and in the latter part of the total cycle as before, and also is pulled again in the latter part of the grand total cycle.

In order to stop the feeding of cards during total taking, another pair of cams on the shafts 261 and 262, said cams not shown but shaped about the same as the cams 326 and 327 of Fig. 15, operate a follower lever 275 (similar to lever 266) to push downward a link 276 (Figs. 8 and 14), which through bell crank 277, link 278 and arm 280 rocks a shaft 281 having thereon an arm 282 in the form of a hook or latch, adapted to engage a shoulder of the link 76 and prevent advance of the card picker 66. In Fig. 14 the parts are shown operated as just described. The sensing chamber 70 for the cards, is closed by the card stop 283 shown closed in Fig. 14. It is moved up to release the card by arms 284 on a rock shaft 285 which is oscillated by a certain cam on the base drive shaft 53, which cam, in this machine holds the stop 283 open only from about 130° to about 200° of cycle. In order to lock the card stop against opening at that time, an arm 286 on the shaft 285, has a lug 287 lying just behind the link 276 so as, when said link is in its depressed position shown in Fig. 14, to lock the shaft against turning counter-clockwise and opening the card stop. The link 276 is cut away on its rear edge at 288, so that when the link is in its normal upper position, the stop is free to open under control of its regular timed cam.

A blank cycle of the instant machine is one in which the card in the sensing chamber, stays there, no card is fed from the hopper 68, and the type bars do not rise to print. It will be seen from the foregoing description, that such a cycle may be produced by rocking the two levers 266 and 275 as shown in Figs. 8 and 14; and it is in that way that the blank cycle of a total taking operation is brought about. It may be remarked that in the instant machine, the lever 275 is rocked to its operated position early in the blank cycle and is held in that position until the end

of the two or three cycles of a total or grand total operation.

The total shaft 251 (Fig. 16) is pulled (rocked clockwise) in the latter part of the blank cycle and held pulled until the latter part of the total cycle, by one or the other of the total cams 291 or 293, having follower lever 289 or 292. Said follower lever 292 operates link 293, lever 294, link 295, bell crank 296 and link 297 the last pivoted to an arm 298 on said shaft 251. On grand total operations, the follower 289 operates follower 292. The bell crank 296 also operates a link 300, bell crank 301, link 302 and arm 303, to rock a shaft 304 which is a part of the line space mechanism of the instant machine. This linkage also operates other devices not shown, but which contribute to total taking.

The grand total shaft 250 (Fig. 18) is pulled by a cam 305 on the grand total cam shaft through its follower lever 306, lever 307, link 308, lever 310, link 311, bell crank 312 and link 313, the latter pivoted to an arm on said shaft 250. The bell crank 312 also operates a link 314 which rocks the same bell crank 301 as the total pull linkage, raising the link 302 to rock the shaft 304. This link train also includes other parts not shown.

Line space mechanism

30 The line space ratchet wheel has been removed from its usual place on the platen shaft and replaced by a ratchet 901 on the hollow shaft 163 in the long feed unit (Fig. 3), which shaft drives the shaft 155 which is geared to the platen. 35 Said ratchet is operated by a line space pawl 902 pivoted at 903 to a plate-like lever 904 and drawn toward the wheel by a spring 905. Said lever 904 is journaled on the hollow shaft 163 and is operated by a link 906, pivoted to an arm 907 fast on the usual line space shaft 908. Said shaft is rocked as usual by a link 910 (Fig. 15) connected to an arm 911 on said shaft and operated by the follower lever 912 of a cam 913 on the drive shaft 63. Said cam is timed to rock the lever 904 counter-clockwise in Fig. 3 to draw the pawl 902 back to engage a fresh tooth of the ratchet at from 135° to 156° of cycle, and to rock said lever clockwise to space the paper at from 180° to 272° of cycle. The extent of line spacing, whether single, double or triple, is regulated by the same means as heretofore for regulating the extent of counter-clockwise rotation of the shaft 908. Fig. 9 is a right hand side view of said means. An arm 914 on the right hand end of the shaft 908, has a pin 915 adapted to be variably arrested by a stepped stop plate 916, loose on the rock shaft 304 hereinbefore referred to and which is journaled in the frame member 105 (Fig. 5). A plate-arm 918 fast on said shaft, has a series of holes 920 adapted to be entered by a plunger pin 921 on the plate 916. By setting said pin in one or another of said holes, the stop plate 916 can be set to permit an extent of motion of the pin 915 for triple, double or single spacing, or for no spacing. A third plate-like arm 922 can be adjusted by a plunger 923 in said arm and a series of holes 924 in the plate 918 to four different settings. When set in the end one of said holes, a finger of the arm 922 is in contact with a fixed stop 925 and prevents counter-clockwise motion of the arm 922, the arm 918 and the shaft 304; but when set in one of the other holes it permits such rotation, and rotation of the stop plate 916, to the extent of one, two or three steps of plate 916. Thus, if the latter plate be set as

shown for single spacing and arm 922, as shown for double spacing, then, on rocking the shaft 304 as far as permitted by the stop 925, the plate 916 will be rocked for triple spacing. The shaft 304 is rocked clockwise by a spring until arrested in its normal position by a fixed stop 926. It may be rocked counter-clockwise preparatory to a total taking cycle, by the link 302 through a spring 927 acting on a pin 928 on the arm 303 fast on said shaft. Said spring normally holds the pin 928 in the upper end of a slot in the link. When, preparatory to a total cycle, said link is pushed upward, the shaft will be rocked until arrested by the stop 925, which will be after said shaft has been rocked three, two or one space, or not at all, depending on the setting of the arm 922. This may afford a spacing after total printing, in excess of that for which the plate 916 is set; and it provides for line spacing after total printing in case the said plate is set for no spacing during item cycles.

In order to hold the line space pawl 902 out of contact with the ratchet 904 at certain times, as shown in Fig. 3, an arm of said pawl is engaged by a pin 931 on a lever 932 pivoted on a rock shaft 933. Said lever is the follower lever to a cam 934 on the shaft 117, which rotates continuously when the machine is in operation. The cam has a short high dwell timed to hold the lever 932 in its pawl-lifting position in the stop position of the shaft. When the machine is not running, the pawl is thus always disengaged from the ratchet to permit backward turning of the platen by hand. The shaft 933 has fast thereon the detent arm 142 (Fig. 2) for the disk 140, and said disk rocks said shaft clockwise when said disk begins to turn. Fast on said shaft is an arm 935 (Fig. 3) to which is attached the spring 936 which controls said shaft and the detent 142, 143. The arm 935 carries a pin 937 which, when the arm rocks clockwise, rocks the lever 932 so as to lift the pawl 902 out of the ratchet while said ratchet is being rotated by the long feed mechanism.

A line space detent wheel 940 (Fig. 2) is mounted on the hollow shaft 163 outside the frame 106, and said wheel is normally engaged by a detent roller 941 on a lever 942 influenced by a spring 943. The detent lever 942 is lifted out of the wheel 940 while the disk 140 is rotating, by a link 945, pivoted to an arm 946 on a rock shaft 947 which shaft, inside the frame 106, (Fig. 5) has an arm 948 connected by a link 950 with an arm 951 fast on the rock shaft 933.

Long feed after total

It is frequently required that, following the printing of a total or a grand total on one form, the paper be advanced to the first or some other predetermined line of the next form. For example, in Fig. 26, the total happened to be printed on line 22 of the illustrated form, and it is desired to advance the paper to line 6 of the next form in order to print the first address or heading line. This feed is initiated by the total linkage shown in Fig. 16. The total cam 290 has a rise from 231° to 339° of the blank cycle, a dwell from there to 231° of the total cycle, and a drop from there to 320° of the total cycle. The link 302 of this linkage, being conveniently located for the purpose, is provided with a stud 315 (Fig. 5) which, when said link rises, rocks a bell crank 316 which, through a link 317, rocks counter-clockwise an arm 318 on the tripping shaft 202. Preferably (see Fig. 6)

the arm 318 is loose on the shaft and has beside it another arm fast on the shaft and having a disabling button 320. When this button is set active, the total linkage above referred to will rock the shaft 202 in the latter part of the blank cycle and hold it rocked throughout most of the total cycle. The shaft 202 carries one of the arms 206 (Fig. 2) which, through a push rod 207, sets the tripping lever 175 which is associated with the innermost line finding disk 148. This disk has its notch 1481 so disposed as to bring the paper to line 6 of the form of Fig. 26. The feed will be effected in the same manner as hereinbefore described.

Preferably, the link 317 acts on the arm 318 through a pin, slot and spring connection 321 which can yield in case motion of the shaft 202 is blocked.

Long feed after grand total

The projecting end of the grand total shaft 250 has an arm 322 (Fig. 18) which, through a yieldable pin, slot, and spring connection, operates a link 323 pivoted to an arm 324 on the projecting end of the tripping shaft 202, (Fig. 6). This arm is loose on the shaft and is operatively connectible with it by a disabling button 325. The tabulating machine has a mode of operation called "totals only," according to which items are not printed, the lines of printing consisting of a series of totals, each from a group of cards. These totals are printed like items, and a grand total is printed at the bottom of the list, whereupon it is desired to feed the paper to the first line of the next form. In that case, the disabling button 325 is set active and the button 320 inactive. In that setting, the shaft 202 is not rocked before group total cycles but is rocked just before grand total cycles, initiating the desired feed. The operation will be described in detail hereinafter.

Credit balance mechanism

A special case arises when the number of items in an invoice is nearly or exactly equal to the number of line spaces provided for items on the form. If, for example, 14 item lines are provided for, and there happen to be just 14 items in some group, then the 15th card will be of a new designation, causing the total taking unit 260 to go into operation to print the total and initiate a long feed to the first heading line. Also, when the 14th item has been printed and the paper is spaced to the 15th line, the pawl 233, 241 (Fig. 2) will be tripped to initiate a capacity feed to the first item line of the next form. To avoid this conflict, means are provided whereby the total control mechanism defeats or nullifies the capacity feed, and the total will be printed on the 15th line, which is herein called the over capacity line. For this purpose, and for other purposes, when applying the invention to the instant machine, a certain "credit balance" linkage has been found suitable and is utilized. Said linkage includes a pair of cams 326, and 327 (Fig. 15) on the shafts 261 and 262, respectively, which, acting through follower levers 328, 329, link 330, bell crank 331, link 332, bell-crank 333 and link 334, rock a so called "credit balance shaft" 335. When any totalizer registers a negative or "credit" balance, this shaft causes it to be set in subtraction condition preparatory to total taking. The cams 326 and 327 pull the described linkage and shaft early in the blank cycle of a total taking operation and hold them pulled until near the end of the total or grand total cycle, as the case may be.

For want of a better term, the mechanism now to be described, is herein called the "credit balance" mechanism, from the accidental circumstance that, in the instant machine, the linkage called by that name operates at the desired time.

The follower lever 329 has been extended rearward and has pivoted thereto a link 336 which rocks a lever 337, 338, (see Fig. 8), which reciprocates a long push link 340. The lever 337, 338, has its two arms off-set, the one from the other, along the fixed post 341 on which it is pivoted. The link 340 extends up into the main paper feed unit (Figs. 3, 6, 14 and 15) where it acts on a stud 342 on an arm 343, fast on a rock shaft 344, to rock said shaft clockwise. Said shaft is urged counter-clockwise by a spring 348. It projects through the frame casting 106 (Fig. 2), and it has fast on its end an arm 345 having a stud 346 extending in front of the upright arm of a piece 347, which is pivoted at 348 to the plate-arm 226 of the capacity feed mechanism. The nose 236 of said arm, is a part of this member 347. A spring 350 urges said member clockwise about its pivot against a limiting pin 359. When the capacity shaft 225 is set and the shaft 344 is pulled, the member 347 is rocked to where the pin 237 escapes beneath the nose 236, and the lever 175 is restored, thus nullifying the capacity setting.

The pin 342 lies in an inverted L-shaped slot 349 in the upper end of the link 340, which latter normally stands as shown in Fig. 3 with the shoulder of said slot under the pin 342; but the link may be swung slightly to the right in Fig. 3 bringing the vertical arm of the slot under the pin, freeing the latter from said link. The forward edge of the link is formed off at right angles, making a flange 3402 (Fig. 4) which is slotted, the flange straddling the arm 343 and constituting a guide for the link. Another arm 3431 fast on the shaft 344, carries a disabling button 339. Fig. 4 shows the link 340 moved by hand to its frontward, inactive position, and the plunger of the button 339 projected behind the flange 3402, holding the link in its inactive position and thus disabling it. For runs where the operation of the link is desired, the button 339 is withdrawn and the link allowed to assume by gravity or a light spring, its active position shown in Fig. 3.

The form shown in Figs. 26 and 27, has single space lines Nos. 13-42 inc. (30 single spaces, or 15 double spaces) appropriated for printing the body of the bill. Taking this form as an example, then in the event that a group of cards numbers just 14, the mechanism as thus far described would be operative to print the total on line 42 and then to feed up the next form to the first heading line. When, after printing the 14th item on line 40, the paper was spaced to line 42, the arm 240 on the drum would trip the pawl 233 and set the mechanism for a capacity feed starting in the latter half of the 15th cycle. But at the end of the 14th cycle, the change of designation would be detected, setting the total control unit into action, and early in the 15th cycle the credit balance linkage would pull the shaft 344, releasing the tripping lever 175 from the nose 236, thus nullifying the capacity setting. Late in the 15th cycle, which is now the blank cycle of total taking, the total linkage would be pulled, rocking the trip shaft 202 and causing an after-total feed starting in the 16th, or total cycle.

When, in the 16th cycle, the drum starts rotating, the arm 240 frees the pawl 233, and the next restoration of the shaft 225 is therefore effective. Near the end of the cycle, the credit

balance linkage and the shaft 344 return to normal and the long feed mechanism is thus normalized.

In the event that a group contains exactly 15 items, the capacity feed would operate normally; that is to say, the 15th item would be printed on line 42 and the paper would then be fed to the first item line (line 14 in Fig. 26). Meanwhile, at about the end of the 15th cycle the change of designation would be detected, and the total taking control mechanism would initiate an after-total feed as above described. The 16th cycle would be the blank cycle of the total taking operation, and the shaft 344 would be rocked; but in this case the capacity feed would be already going on, and the rocking of said shaft would be too late to nullify it. The total would be printed alone on the second form, and the paper immediately fed to the first heading line of the next succeeding form.

The mode of operation as far as just briefly recounted, is much the same as in the prior application Serial No. 522,720, though the mechanism has been modified from that described in said prior application.

Blank cycle mechanism

There is an objection to having a total appear alone on a form, with no designatory matter to show to what account or invoice it relates. Means are therefore provided to assure that, where, in the above example, the number of items is more than 14, the 15th item will be carried over to the second form. With the mechanism as thus far described, the difficulty arises from the fact that, where there are just 15 cards in a group, the capacity feed was tripped in spacing to the 15th line, and the fact that the 16th card was of a new group, was not detected until near the end of the 15th cycle, after the long feed had already begun. To cure this, means are provided whereby the capacity tripping device (arm 226 and shaft 225, Fig. 2) also initiates a blank cycle, during which no card feeding or printing occurs and during which the capacity feed to the first item line of the next form occurs, and during which the 15th card is retained in the sensing chamber. The 15th item is therefore printed on the second form, regardless of whether or not the 16th card proves to be of a new group. The sensing of the 16th card is thus delayed until after the 15th item has already been printed on the second form. Mechanism to the above specified effect is also described in the prior application Serial Number 522,720.

The blank stroke is brought about by a long pull link 351 (Figs. 3, 6, 8 and 14) pivoted to one arm of an off-set lever 352 (Figs. 8 and 14), pivoted on the post 341, where it is nested in the lever 331, 338. The other arm of said lever 352 carries a link 354 which is pivoted at 355 to a rearward prolongation of the follower lever 266 of the slam bail linkage of the total control mechanism. The construction is such that if the link 351 be pulled up as shown in Figs. 8 and 14, said slam bail linkage will be operated, pulling the slam bail shaft 252 and the designation shaft 253 to lock down all of the type bars controlled by said shafts.

In order to interrupt the card feed, the link 354 is prolonged downward, its lower end standing above a post 356 on the link 276. When the link 351 is pulled, the link 276 is therefore depressed, locking the card stop 283 and the picker

as hereinbefore described. Pulling the link 351 therefore causes a blank cycle.

This blank stroke linkage, as thus far described, is substantially the same as is described in the application Serial Number 522,720. The means for pulling, retaining and releasing the link 351 have been improved as will now be described.

The link 351 is pulled to produce a blank cycle, by a cam 357 on the cam shaft 116, the end of whose follower lever 358 (Fig. 3) acts on a pin 360 projecting from said link, as shown in Fig. 14. Said follower lever vibrates once at every machine cycle, its free end being at the top of its stroke at about the end of the cycle; but normally the link 351 stands as shown in full lines in Fig. 3, with its pin 360 out of range of said lever. It is pulled rearward into range by a link 361, connected by pin, slot and spring 362 with an arm 363 (Fig. 3) loose on the capacity trip shaft 225. When, at, say, 214° of a cycle, the arm 226 is tripped off by an over-capacity spacing of the paper, and swings clockwise in Fig. 2, the arm 363 is rocked clockwise in Fig. 3, by a pin 364 on the arm 227 which is fast on the shaft 225, causing the link 361 to pull the link 351 to where its pin 360 is over the lever 358; and said link 351 will be pulled upward at the end of the cycle (broken lines in Fig. 3) to cause the next cycle to be a blank one. When the link 351 is pulled rearward, it moves slightly toward the rear a latch slide 365 mounted as shown in Figs. 3 and 24 on the horizontal portion 1064 of the frame piece 106. Said latch is slotted for limited sliding movement on two pins and is urged forward by a spring 366. When the arm 358 lifts the link, this slide snaps in under a shoulder 369 of the link and holds the latter in its pulled position (broken lines in Fig. 3).

The blank cycle linkage is restored to normal position toward the end of the cycle, by pulling the link forward, free of the latch 365, and allowing it to drop down to its normal position. In the instant machine a certain rock shaft 367 (Fig. 14) is conveniently located and suitably timed for the purpose. It is one of two rock shafts used to restore the type bar stops 90 (Fig. 1). An arm 368 (Figs. 14 and 17) mounted on it has a pin 370 projecting into the plane of a dog 371 which is pivoted at 372 to a bracket 373 fast on the link 351. In the normal position of the parts as shown in Fig. 19, the dog 371 stands lower than and a sufficient distance forward of the stud 370, leaving the link 351 free to be swung rearward. A pin 374 on said dog is normally held by a spring 375 against the under edge of said bracket, permitting the dog to yield downward.

Operation of blank cycle mechanism

The operation of this device in producing a blank cycle of the machine under control of the capacity feed, is illustrated in Figs. 19-23. In the time chart, the movements of the upper end of the link 351 rearward into and forward out of engagement with the lever 358, herein called, respectively, "in" and "out," are traced in line C; and the up and down movement in line D. Fig. 19 shows the parts in normal position, with the link 351 down and the stud 369 out. At 214° of the 14th item cycle, the stepping of the paper trips the capacity shaft 225 and draws the link 351 in, bringing stud 369 over lever 358. Fig. 20 shows the parts at 304°, when the shaft 367 has nearly finished rocking, swinging the stud 370 over the upper edge of the dog 371, and the cam 357 is about to start to raise the link 351.

Fig. 21 shows the parts at 335° when the lever 358 has rocked, pulling the link 351 up to its effective position, and the latch 365 has snapped under the shoulder on said link to retain it in that position. The upward motion of the link caused the dog 371 to be deflected downward by the stud 370. Fig. 22 shows the parts at 49° of the blank cycle, when the stud 370 has swung back free of the dog 371, which has snapped up in front of it. These parts remain in this position until the stud 370 again swings clockwise at from 267° to 318° of the blank cycle, pushing the link 351 out permitting said link to drop back to the normal position shown in Fig. 19. Fig. 23 shows the parts at, say, 312°. The stud 370 has just pushed the link 351 out (free of the lever 358) and said link is falling, being held out by the stud 370. The lever 358 has started to rock. By the time the dog 371 on link 351, has fallen free of the stud 370, the end of the lever 358 will have reached so high a position that, when the link 361 tends to pull the link 351 rearward, the stud 360 will strike against the end of said lever and prevent such movement. The link will resume its in movement when said lever returns to normal. At from 72° to 102° of the item cycle, the cam 192 (Fig. 3) will restore the capacity shaft 225 which, this time, will be caught by the latch 233, and the whole mechanism will be at normal.

The operation of the blank stroke mechanism when, after the capacity shaft 225 has been tripped, the regular total control mechanism of the machine itself produces the blank cycle of a total taking operation, is traced in the time chart in lines J and K which lines are continuations of the portions of lines C and D ending at line x-x. As indicated in line C, the link 351 is drawn in at 214° of the 14th cycle as before, by the rocking of the capacity shaft 225, it being remembered that the arm 240 holds the latch 233 tripped until after the long feed starts, that is to say, until some time after 186° of the total cycle. The time chart shows where, in each cycle at 102° and again at 286° the two humps of the cam 192 momentarily restore the shaft 225, permitting the link 351 to move out. As shown in line D, said link is pulled up by the lever 358 at 330° of the 14th cycle, as before, and the parts go through the same movements as are shown in Figs. 19-23. Early in the blank stroke the regular total control mechanism goes into operation and its slam bail cam 263 would itself hold the link 351 up. This makes no difference except that when, at 314° of the blank cycle, the stud 370 moves the link out, said link does not fall abruptly, but is let down gradually by the slam bail cam. It escapes the lever 358, and the blank stroke is not repeated. The slam bail cam moves the link 351 up again in the early part of the total cycle, but lets it down again near the end of that cycle in the same way as hereinbefore described; that is to say, the stud 360 on the link comes down in front of the end of the lever 358, which is rising at the same time, and again the blank stroke is not repeated. Meanwhile, at 186° of the total cycle, the drive disk 140 begins to rotate, and presently frees the latch 233 of the capacity mechanism, so that when, at 102° of the first cycle after total, the shaft 225 is restored, it is latched in normal position, and the whole mechanism has returned to normal.

It may be remarked at this point that as will be explained hereinafter, the machine may be

set up to print totals only, instead of items, and to feed the paper to the next form after printing a grand total. The operation of the blank stroke mechanism is the same in that event as above described, but occurs later.

Isolated total

It is sometimes desired to print the total, not immediately beneath the last item, but on some predetermined line at or near the bottom of the sheet; and a total so printed is herein called an "isolated total." The mechanism described in application Serial No. 522,720 contains no provision for this operation.

An arm 383 (Fig. 2) is mounted on the shaft 15 344 and operatively connected therewith by a disabling button 384. A pin 385 on said arm, operates a link 386 which is pivoted to the rear arm of one of the tripping levers 175, viz., as here shown, the second one from the observer in Fig. 2. When the button 384 is set active, a rocking the shaft 344 therefor "sets" said tripping lever. A slot 387 in the link 386, permits said tripping lever to be operated as, for example, from a control hole in a card, independently of said shaft.

The operation is as follows: Assuming that the disabling button 399 is out, and the link 340 is therefore active, the shaft 344 is rocked clockwise in Fig. 2, early in the blank cycle of a total taking operation, rocking the tripping lever 175 to its set position. The universal tripping frame 186 advances soon thereafter, tripping the latch 171 and the clutch dog 180, by 176° of the blank cycle. The disk 140 rotates from 186° of the blank cycle to 126° of the total cycle (as shown in broken lines in Fig. 30, line L), advancing the paper to the predetermined line before the printing of the total at 165°. The line finding disk 151, of course, has its notch 1511 cut in such a position as to bring the paper to the desired line.

However, the link 340 is held in its upper position till late in the total cycle, and, unless means to the contrary were provided, the link 386 would still be holding the tripping lever 175 in set position at the time (126°-176°) when the universal tripping frame 186 again advances, and a second long feed would be initiated. To prevent this, and for other reasons, means are provided to free the shaft 344 from the link 340. The means shown in the drawing consists of an arm 376 (Figs. 3 and 28) loose on the total trip shaft 202 and connectable to rock therewith by a disabling button 377 whose plunger is adapted to enter a hole in an arm 378 whose hub is fast on said shaft. The arm 376 is made bail-fashion and straddles the hub of the arm 378. Said arm 376 has a stud 380, standing behind the link 340. In isolated total operations, the button 377 is set in (active). The shaft 202 is rocked in the latter part of the blank cycle, after the long feed has been started, and the stud 380 pushes the link 340 forward until the vertical leg of the slot 3401 comes under the stud 342, permitting the shaft 344 to return to normal position. When an isolated total is not desired, the disabling buttons 339 and 384 are set out.

After the printing of an isolated total, it is usually desired to advance the paper to the next form. With forms of the sort shown in Fig. 26, this may be done by the regular after-total feed hereinbefore described. The total shaft of the machine is pulled in the latter part of the blank cycle, resulting in an upward movement of the

link 302, (Figs. 5 and 16), rocking lever 316 and pushing link 317 rearward, rocking the total tripping shaft 202, and setting the total space tripping lever 175. At this time the disk 140 and its appurtenances are already rotating and the universal tripping frame 186 has returned to its normal position. The moving of the total tripping lever to its set position does not bring it into the range of those parts, which complete their rotation at 126° of the total cycle. At 140° of that cycle, the universal tripping frame again begins its advance, tripping the latch 171 and the clutch after the printing, as in any other after-total feed.

Non-list of items, long feed on grand totals

Fig. 27 shows a form of invoice having a heading for the name and address of a customer and a body in which are printed a list of group totals, followed by a grand total. Each group represents a series of items, such as ham, bacon, etc., all grouped under "pork," a similar total of difference cuts of beef, etc. The individual items are not printed. The requirements are, that after each grand total the paper is to be fed to the first heading line of the next form, and in case of over-capacity the paper is to be fed to the first group total line of the next form. Also at least one group total is to be printed on every form, no grand total to appear alone on a form. Also, when the group total printed on the capacity line of a form proves to be the last for that customer, the grand total is to be printed below it on the same form, no capacity feed being effected. It is also usual to set the machine so that on the first item cycle after a total, the designation ("Pork," "Beef" etc., in Fig. 27) of the new group is printed on the line for the total of that group.

How the instant machine is set up to print only totals and grand totals, is explained in the Mueller Patent 2,381,361. The only feature of it that affects the spacing of the paper is, that the line space control device shown in Fig. 9 has the plunger 921 set for no line spacing on item cycles and the plunger 923 set to afford spacing (single, double or triple) after printing a total. For the form shown in Fig. 27, it is set for double spacing after a total. In order to effect this program of paper feed, and for certain other reasons, an additional linkage is provided, as shown in Fig. 16. The follower lever 289 for setting the mechanism for a total cycle, is prolonged rearward beyond its pivot and is connected by a link 395, lever 396 and link 397, with the arm 3431, which is fast on the rock shaft 344. The pivot pin on the lever 396 lies in a slot in the link 397 to allow the latter to move upward without operating the total mechanism. The inner end of the follower lever 289 lies beneath the inner end of the follower lever 292, which is operated by the total cam 290 on the total shaft 261. The construction is such that, on a grand total operation the lever 289 is rocked preparatory to the total cycle, and it rocks the lever 292 and operates the parts connected with the latter lever; but on a group total operation, the cam operates the lever 292 but not the lever 289. It results that on a group total operation, the linkage just described is not operated, but on a grand total operation, said linkage is pulled in the latter part of the blank stroke pulling the shaft 344; and it remains pulled throughout the greater portion of the total stroke.

For this job, the disabling buttons are set as

follows: As a capacity feed is desired after the 14th total, the button 339 (Fig. 4) is in, so that the link 340 is inoperative to pull the shaft 344 and thus defeat that feed. Button 384 (Fig. 2) is out, as no isolated total is wanted. Button 320 (Fig. 5) is out, so that no long feed occurs after a group total. Button 325 (Figs. 6, 18 and 28) is in, to cause a long feed after a grand total. Group designations are P, B, M, etc., (Fig. 27) and grand total designations are the customers' 10 numbers, 125, 126, etc. Designations are printed from the first card of each group, in the manner usual with the instant machine.

In operation, the customer's name and address are printed in the heading from two or more cards, the last one of which contains a control hole to cause a long feed to the first line of the body of the invoice, the same as hereinbefore described. The cards of the first or "P" group are then tabulated, without printing except that the designation is printed from the first card. 15

A change of group designation initiates a group total operation, late in the blank cycle of which, total cam 293 (Fig. 16) pulls the total linkage, but does not pull the linkage 395, etc., leading to the shaft 344. It also pulls the link 317 through link 302, but the button 318 is out, and no long feed is initiated. After the total cycle, the "B" group of cards is tabulated and its total printed; and so on, until the grand total designation changes. The blank cycle and total cycle of the grand total operation are the same as above described, except that they are controlled by the grand total cam shaft 262. Preparatory to the total cycle, the follower lever 289 is rocked, rocking the lever 292 and pulling the total linkage the same as before. The lever 289 also pulls the shaft 344 as above described, and holds it pulled until near the end of the total cycle; but this operation is without practical effect. In 40 the total cycle, the group total is printed and the paper line spaced. In the latter part of that cycle, the grand total shaft 250 is pulled, and through link 323 (Fig. 18) the shaft 202 is rocked preparing for a long feed to the first heading line 45 of the next form; after the grand total is printed in the grand total cycle. The paper is thus advanced to the first heading line.

When, as illustrated in Fig. 27, the number of group totals in an invoice happens to be just equal to the capacity of the form, so that the last total is printed on the 40th or "capacity line," the operation is as follows: When the last item of the last group is tabulated, the next card effects a change in grand total designation instead of merely a group total, and the mechanism begins to operate as just above described; but the group total printed on the capacity line is the group total of a grand total operation, to be followed immediately by the printing of the grand total. The total is printed at 165° of the total cycle, and the paper line spaced to the over-capacity line; tripping the capacity feed at 214° of the total cycle.

At this time: (a) the stud 370 is standing locked in its forward position (Fig. 23) where it remains until 360° of the grand total cycle; and (b) the link 351 is held in its upper position by the slam bail cam in the total control unit. The dog 371 is, therefore, standing up behind the stud 370, and the link 351 is thus held in its forward position against the pull of the spring 362. The rocking of the capacity shaft 225 therefore cannot pull said link into engagement with the follower lever 358.

The total control unit holds the link 351 up until 300° of the total cycle, when it starts to descend, reaching its bottom position at 20° of the grand total cycle. The dog 371 does not escape from the stud 370 until it has nearly reached the bottom of its descent. When it does escape, the spring 362 pulls it rearward, but by this time the follower lever 358 has completed its stroke, and the grand total cycle is therefore not made a blank one. At 75°-150° of the grand total cycle, the total control unit again moves the link 351 to its upper position, while said link is in its rearward, or active position, with the dog 371 under the stud 370. Said stud therefore deflects the dog downward. At 102°, the cam 292 momentarily restores the shaft 225, causing the link 351 to swing forward to its inactive position, thus moving the dog 371 free of the stud 370, whereupon said pawl snaps up in front of the stud, which holds the pawl and the link inactive until near the end of the grand total cycle. Until then, the stud 370 has been held in its forward position by the lock controlled by the grand total linkage. This lock is released around, say, 275° of cycle, by the restoration of said linkage, and the stud 370 then goes back to its normal position; but the dog 371 is still in front of it, link 351 being held up by the slam bail cam. When, therefore, at 267°-313°, the shaft 357 and stud 370 make their regular forward swing, said stud swings the link 351 and its stud 360, free of the follower lever 358, and no blank stroke is initiated. Late in the grand total cycle, or early in the next cycle, the after-grand-total feed frees the latch 233 from the arm 240, and when, at 102° of said next cycle, the shaft 225 is restored, by its cam, it is caught by said latch.

This total cycle was prepared for, not by the cam 293 (Fig. 16) but by the cam 291, whose follower lever had pulled the linkage 395, etc., and pulled the shaft 344, moving the stud 346 (Fig. 2) to its rear position. When, therefore, the capacity arm 226 rocked clockwise at 214° of cycle, the lever 347 was deflected by said stud, swinging the nose 236 upward and causing it to pass above the stud 237 on the tripping lever 175, without setting said lever. The capacity feed is thus defeated and the grand total is printed on the over-capacity line. Meanwhile, the link 323 (Fig. 18) has pulled the shaft 202 and set the mechanism for a long feed to the first heading line, which feed occurs after the printing of the grand total.

Capacity feed when printing totals only

When the number of group totals to be printed exceeds the capacity of the form, the operation is as follows: The change of designation which causes a total to be printed on the capacity line is a group change only, and not a grand total change. The operation is as just above described except that the total pull is effected in the blank cycle by the cam 293 (Fig. 16) which does not pull the shaft 344. When, therefore, in the total cycle the total has been printed on the capacity line, the capacity feed occurs the same as when listing items. That is to say, the arm 240 (Fig. 2) on the drum 146, depresses the pawl 233 and holds it down as long as the paper stands at the over-capacity line, allowing the arm 226 and shaft 225 to rock clockwise. Said shaft and arm are momentarily restored at 286° of the total cycle and again at 102° of the next cycle, by the cam 232; but they drop back and are in their set position when the universal tripping frame ad-

vances at 126°-176° of said first cycle following the total, initiating the long feed to the first body line of the next form. Such long feed will begin at 186° of the first cycle after total. If it were not for the blank cycle mechanism, the designation of the new group of cards would be printed in that cycle, on the over-capacity line; and the capacity feed would occur immediately thereafter; and the total of said new group would be printed on the first item line of the next form. The blank stroke, which occurs the same as when printing items, delays the printing of the designation until after the long feed, thus avoiding the error of printing the designation and the total not only on different lines, but also on different forms.

Isolated grand total

For this operation the tabulating machine is set up for listing totals only, as above mentioned. In the long feed mechanism, the disabling button 384 (Fig. 2) is set active so that a rocking of the shaft 344 will set the tripper 175 associated with the isolated total line disk 151. The link 340 (Fig. 3) is set in its inactive forward position and retained thereby by the disabling button 339 (Fig. 4). The shaft 344 will, therefore, not be rocked on group total operations, but on a grand total operation it will be rocked by the link 397 (Fig. 16) in the latter part of the blank cycle. When the universal tripping bar 186 advances at 176° of the total cycle (after the last group total has been printed), the tripper 175 sets the feed pawl 166 and trips the clutch, and the paper is advanced to the grand total line where the grand total is printed. For this operation, usually the disabling button 320 was set inactive (Fig. 5) and the button 325 (Fig. 18) active, so that the pulling of the grand total linkage set the mechanism for an after-grand total feed to the first heading line of the next form.

Various changes may be made in the details of construction and arrangement without departing from the invention.

Having thus described my invention, what I claim as new and desire to secure by Letters Patent is:

1. In the long paper feed mechanism of a machine of the class described, the combination with a paper impelling device, a continuously rotating drive shaft, a line finding drum geared to the paper impelling device, one or more drive pawls to rotate said drum differentially but normally out of engagement therewith, and a normally disengaged clutch to connect said drive shaft to rotate said pawl or pawls, of a universal tripping bar having a timed movement at each cycle of the machine, one or more trippers, one for each of said drive pawls, means to set said tripper or a selected one of said trippers into the path of movement of said tripping bar to be operated thereby, means whereby a tripper when operated by said bar causes its associate drive pawl to be set to active position, and a clutch dog released by the operated tripper to engage the clutch.

2. In long paper feed mechanism of the sort described comprising a continuously rotating drive shaft, a line finding drum geared to a paper impelling device, one or more line finding drive pawls normally out of engagement with said drum, and a normally disengaged clutch by which said pawls are connectible with said drive shaft, the improvement which resides in the combination of a universal tripping bar having a timed movement at each cycle of the machine, a tripper

5

for said pawl or for each of said pawls, means to set a said tripper into the path of movement of said tripping bar to be operated thereby, means whereby said tripper when so operated causes its associate pawl to engage said drum, and means whereby said tripper when so operated engages said clutch.

3. In long paper feed mechanism of the class described, the combination with a paper impelling device, a set of differentially toothed line finding disks, feed pawls one for each said disk and each having a latch, a drive disk on which said pawls are mounted, and a drive shaft and clutch to drive said drive disk, of tripping levers one for each said latch, a universal tripping frame having timed advance and return movements, means to set a selected one of said tripping levers in position to be operated by said tripping frame, said lever when so operated trips its associate latch, and means actuated by whatever tripping lever is so operated to trip said clutch.

35

4. In paper feed mechanism, the combination with a paper impelling device, a step-by-step line space device, and a line finding drum geared to said impelling device, of a capacity member spring urged to active position, a latch normally holding said member inactive, an arm rotating with said drum and acting to trip said latch when the paper steps past a capacity line thereof, a tripper set to an intermediate position by said capacity member on the resulting movement thereof, a timed member to operate the set tripper, means controlled by said tripper to rotate said drum to feed the paper to a predetermined line thereof, and a cam to restore said capacity member to inactive position.

50
55

5. In paper feed mechanism of the class described, the combination with a paper impelling device, a line finding drum geared to said device, a rotary support, a line finding pawl mounted on said support for driving said drum but normally out of engagement therewith, a drive shaft and a clutch to couple said support to said shaft, of a capacity shaft spring urged to active position, a latch normally holding said capacity shaft inactive, a tripping lever for said pawl and clutch set by said capacity shaft, an arm on said drum to trip said latch and hold it tripped when the paper steps beyond the capacity line after the printing of an item, timed means acting through said tripping lever to trip said line finding pawl and said clutch in the cycle following such printing, and timed means to restore said capacity shaft at each cycle of the machine, the last said means restoring said shaft only momentarily until the rotation of said drum by said pawl causes said arm to release said latch.

6. In paper feed mechanism of the class described, and applied to a tabulating machine having means to produce a blank cycle, a combination with a paper impelling device, the feed drum geared to said device, a line finding pawl to turn said drum for a capacity feed, but normally out of engagement therewith, a rotary support on which said pawl is mounted, a drive shaft and a clutch to couple said support to said shaft, of a capacity shaft spring urged to active position, a latch normally holding said shaft inactive, a tripping lever for said pawl and clutch and set by said capacity shaft, an arm on said drum to trip said latch and hold it tripped when the paper steps beyond the capacity line after the printing of an item, timed means acting through said tripping lever to trip said line finding pawl and said clutch in the cycle following

such printing, timed means to restore said capacity shaft at each cycle of the machine, the last said means restoring said shaft only momentarily until the rotation of said drum by said pawl causes said arm to release said latch, a timed cam to operate said blank cycle means, a follower lever operated by said cam, a blank cycle link to connect said lever with said blank cycle means but normally out of engagement with said lever, a linkage operated by said capacity shaft to draw said blank cycle link into engagement with said follower lever, a latch to hold said link in its pulled position, and timed means to move said blank cycle link out of engagement with the last recited latch.

7. In a record controlled tabulating machine for printing recorded data and adding recorded numbers and in paper feed mechanism of the class described, the combination with the total taking control mechanism of the machine having provision for executing total taking operations involving a blank cycle, a total cycle and a grand total cycle, a paper impelling device, a feed drum geared to said device and including a line-finding disk to feed the paper to a predetermined line position, a feed pawl to drive said line-finding disk, but normally out of engagement therewith, a drive shaft and a clutch to connect said drive shaft to rotate said feed pawl about said drum, of a tripper to trip said feed pawl into engagement, a total tripping shaft (202) to control said tripper, a link operated by said total taking control mechanism preparatory to a total cycle and connectible with said tripping shaft by a disabling button, and a second link operated by said total taking control mechanism preparatory to a grand total cycle and connectible with said tripping shaft by a disabling button, whereby by enabling one of said links and disabling the other, said tripping shaft may be set up to cause said tripper to be set either for a total feed or for a grand total feed as desired; and timed means under control of said tripper to trip said clutch.

8. In a record controlled tabulating machine for printing recorded data and adding recorded numbers and in paper feed mechanism of the class described, the combination with the total taking control mechanism of the machine having provision for executing total taking operations involving a blank cycle, a total cycle and a grand total cycle, a paper impelling device, a feed drum geared to said device and including a line-finding disk to feed the paper to a predetermined line position, a feed pawl to drive said line-finding disk, but normally out of engagement therewith, a drive shaft and a clutch to connect said drive shaft to rotate said feed pawl about said drum, of a tripper to trip said feed pawl into engagement, an isolated total tripping shaft (344) to control said tripper, a link operated by said total taking control mechanism to operate said tripping shaft early in a blank cycle preparatory to a long paper feed prior to the printing of the total and said link disconnectible from said shaft by a disabling button, a second link operated by said total taking control mechanism late in a blank cycle and operating said tripping shaft preparatory to a long paper feed prior to the printing of a grand total, whereby when the first recited link is set active the paper will be fed to a predetermined line before total printing and

when said first recited link is set inactive the paper will be fed to said predetermined line before the printing of a grand total.

9. In a machine of the class described having means for adding numbers and printing on a web of paper divided into forms, and in paper feed mechanism comprising a paper impelling device, a differential line finding drum geared to said device, line pawls settable to drive said drum and a drive shaft connectible to operate said pawls, the combination of means to set one of said pawls to feed the paper to a line of the next form in case of over-capacity, total taking control mechanism including means to cause the machine to execute a blank cycle, a total cycle and a grand total cycle, a shaft (344) having means to reset said preparatory means, means (340) operated by said total taking control mechanism to pull said shaft early in the said blank cycle, a disabling button (339) for said pulling means, means (391) operated by said total taking control mechanism to pull said shaft late in a blank cycle, means (388, etc.) settable by said shaft (344) to cause another of said pawls to feed the paper to an isolated total line, and a disabling button (384) for the last recited means, whereby in one setting of said disabling buttons (339 active and 384 inactive) said shaft will prevent a capacity feed on the blank cycle of a total taking operation, in another setting of said buttons (339 inactive and 384 inactive) said shaft will prevent a capacity feed on the total cycle, in a third setting (339 active and 384 active) said shaft will initiate a feed to said isolated total line preparatory to total printing, and on a fourth setting (339 inactive and 384 active) will initiate a feed to said isolated total line preparatory to grand total printing.

10. In the long paper feed mechanism of a machine of the class described, the combination with a paper impelling device, a continuously rotating drive shaft, a line finding drum geared to the impelling device, a plurality of drive pawls to rotate said drum differentially but normally out of engagement therewith, and a normally open clutch to connect said drive shaft to rotate said pawls, of a plurality of trippers one for each drive pawl, selection mechanism to select and move a tripper to a position intermediate its active and inactive positions, means to operate the selection mechanism, a universal tripping bar having a timed movement at each cycle of the machine to engage a tripper in the intermediate position and to move it to its active position to cause its associate drive pawl to be set to active position, and a clutch dog released by the tripper moving from the intermediate position to active position.
